Attorney

UNITED STATES PATENT OFFICE.

ISAAC HIGGS, OF NEWPORT NEWS, VIRGINIA.

PROPELLER.

Application filed September 6, 1922. Serial No. 586,511.

To all whom it may concern:

Be it known that I, ISAAC HIGGS, a citizen of the United States, residing at Newport News, in the county of Warwick and State 5 of Virginia, have invented certain new and useful Improvements in Propellers, of which the following is a specification, reference being had to the accompanying drawings.

This invention relates to improvements in 10 propellers and an important object of the invention is to provide a propeller construction which lessens the frictional resistance of the water to the propeller.

A further object of the invention is to 15 provide a combined shaft and propeller construction, the construction of the propeller and shaft being such that the formation of abrupt shoulders upon the shaft of the propeller is eliminated and accordingly a considerable head resistance removed as regards 20 the ordinary construction of propeller and shaft.

A still further object of the invention is to 25 provide a propeller construction which permits of a slight reduction in the over all diameter of the propeller and which eliminates the vibration of the propeller in churning of the water commonly presented.

An additional object of the invention is to 30 provide a device of this character which is simple in its construction and arrangement, durable in service and a general improvement in the art.

These and other objects I attain by the 35 construction and arrangement shown in the accompanying drawings wherein for the purpose of illustration is shown a preferred embodiment of my invention and wherein like reference characters designate like parts 40 throughout.

In the drawings:—

Figure 1 is a rear elevation of a propeller constructed in accordance with my invention;

Figure 2 is a side elevation, parts being broken away;

Figure 3 is a front elevation of the hub portion of the propeller;

Figure 4 is a section on the line 4—4 of 50 Figure 2; and

Figure 5 is a sectional view taken through the hub at right angles to the view shown in Figure 4.

Referring now more particularly to the 55 drawings, 10 indicates the hub of a propel-

ler and 11 the blades thereof. In accordance with my invention the hub 10 is provided intermediate the blades 11 or the base portion of these blades with grooves 12, reducing the diameter of the hub and forming 60 thereon shoulders or vanes 13 aligning with and having substantially the same pitch as the base portion of the blades with which they are integrally connected. In the formation of the grooves 12, the groove has its 65 greatest depth at a point adjacent the front of the leading face of the vanes 13 so that these vanes are provided with an abrupt leading shoulder 14, the depth of the groove gradually tapering to the top of the next 70 succeeding vane 13 so that a gradual trailing shoulder 15 is formed upon the vanes providing for the vanes a positive backing for resistance against pressure applied to the blades during rotation of the propeller. 75 These grooves are extended throughout the length of the hub so that the shoulders or vanes 13 extend to the opposite ends of the hub, terminating at such opposite ends in relatively abrupt tapered portions 16, which 80 shoulders during rotation of the propeller form an entering wedge imparting a movement to the water which permits the blades 11 to engage therewith without the usual whipping vibration and without the usual 85 churning action which the propeller has during rapid rotation.

I am aware that previous attempts have been made to accomplish these objects by continuing the metal of the blades to form 90 a ridge or shoulder but in order to accomplish this the blade has been connected with the ridge or vane 13 a sufficient extent to impart considerable movement to the water and thereby cause excessive slipping 95 of the propeller in its action. Furthermore, the majority of these devices are defeated by reason of the fact that the vane 13 extends into the water at a point where it is in constant turmoil due to the fact that the 100 forward end of the propeller hub is of considerably larger size than the shaft to which it is applied. In accordance with my invention I provide the shaft, indicated at 17, with rearwardly extending substantially 105 conical enlargements 18. Beyond this conical enlargement the shaft is reduced to form a shoulder 19 abutting the end of the propeller hub and a tapered portion 20 adapted to fit within the tapered bore of the pro- 110

steller. The shoulder 19 has its rear face of substantially the same diameter as the reduced diameter of the hub, caused by the formation of the grooves 12, and accordingly the water will not have any abrupt surfaces against which it will clash to cause disturbance but will engage smoothly with the hub thereby considerably relieving the ordinary frictional resistance present in 10 practically all types of propellers with which I am familiar.

From the foregoing it is believed to be obvious that a shaft and propeller construction in accordance with my invention is particularly well adapted for use in that the reduction of friction and smooth engagement of the propeller accomplished by this construction will materially increase the efficiency of the propeller to permit smooth 20 operation thereof and thereby relieve the strain upon the machinery and generally reduce the operating cost of propeller mechanisms. It will furthermore be obvious that the construction as hereinbefore set forth 25 is capable of some change and modification without materially departing from the spirit of my invention and I accordingly do not limit myself thereto except as hereinafter claimed.

30 I claim:—

1. A propeller embodying the usual hub and blades, the hub being provided intermediate the bases of the blades with spiral grooves having the same pitch as the bases 35 of the blades and of a width equal to the

distance between adjacent faces of the bases of the blades, said grooves reducing the diameter of the hub and forming thereon spiral vanes aligning with and having the same pitch as the bases of the blades. 40

2. A propeller embodying the usual hub and blades, the hub being provided intermediate the bases of the blades with spiral grooves having the same pitch as the bases of the blades and of a width equal to the 45 distance between adjacent faces of the bases of the blades, said grooves reducing the diameter of the hub and forming thereon spiral vanes aligning with and having the same pitch as the bases of the blades, said grooves having their greatest depth at a point adjacent the leading face of said vanes and tapering in depth gradually to the next adjacent vane. 50

3. In combination with a propeller embodying the usual hub and blades, the hub being provided intermediate the bases of the blades with grooves forming vanes aligned with and having substantially the same pitch as the bases of the blades, said hub having a bore and a shaft engaged with said bore and provided with a forwardly tapering enlargement having its rear edge terminating in an abrupt shoulder having a diameter substantially the same as the 55 diameter of said hub at the base of said grooves. 60

In testimony wherof I hereunto affix my signature.

ISAAC HIGGS.
